UNITED STATES PATENT OFFICE.

ANTOINE LACROIX, JR., OF BROOKLYN, ASSIGNOR TO THE CO-OPERATIVE BUILDING PLAN ASSOCIATION, OF NEW YORK, N. Y.

DESIGN FOR THE EXTERIOR OF A COUNTRY HOUSE.

SPECIFICATION forming part of Design No. 19,371, dated October 22, 1889.

Application filed September 28, 1889. Serial No. 325,454. Term of patent 3½ years.

To all whom it may concern:

Be it known that I, ANTOINE LACROIX, Jr., of the city of Brooklyn, in the county of Kings and State of New York, have invented and 5 produced a new and original Design for the Exterior of a Country House, of which the following is a specification, reference being had to the accompanying drawings, forming a part thereof.

10 Figure 1 represents a perspective view of a country house showing my design. Fig. 2 is a plan of the first story thereof.

Similar letters designate corresponding parts in both the figures.

15 A house of this design consists of two stories, the upper story being included within a gable roof, the first story being in plan of the form of a parallelogram and having at the front and two sides a piazza, and the second 20 story being included partly at the back and wholly in front within a gable roof, the ridge of which is parallel with the front of the house, and the front part of which is continued downward to include the piazza, the portions of the 25 piazza at the sides of the house being covered by shed roofs and the front corners of the piazza being covered by a small gable roof, the front of which forms a continuation of the front of the roof of the house. In front of the 30 second story there is a balcony springing from

the portion of the roof over the piazza, and behind and over this balcony there projects from the main roof a gable. The plan of the house forms a parallelogram. The front wall is of the height of the first story only. 35 The side walls B, only one of which is visible in Fig. 1, are both alike—flat—and run up and through the first and second stories into the gables of the roof C. In front of the house the roof is continued downward, as shown at 40 C', Fig. 1, to form also the roof of the front of the piazza P. The piazza at the sides of the house has shed roofs D, and these shed roofs are connected with the portion C' of the front roof and form two small gables D on each side 45 of the house.

E designates the balcony springing from the portion of the front roof over the piazza, the said balcony being of rectangular form.

F designates the gable projecting from the 50 main roof C over the balcony E.

What I claim is—

The design for the exterior of a country house, substantially as herein shown and described.

ANTOINE LACROIX, JR.
